RECLAIMING SPENT DOCTOR SOLUTIONS

Robert A. Dunham, Long Beach, Calif., assignor
to Union Oil Company of California, Los Angeles, Calif., a corporation of California

Application December 24, 1928, Serial No. 328,259

8 Claims. (Cl. 23—51)

This invention relates to a process and apparatus for treating sulfur-containing oils with sodium plumbite or analogous lead compounds for the purpose of removing sulfur of the type known as "sour sulfur", and includes method and apparatus for recovering the spent lead compounds which have been passed through the process. It is particularly directed to the treatment of gasoline-like compounds or petroleum fractions or analogous fractions which contain sulfur compounds which are reacted on by sodium plumbite. Compounds which are so reacted on are, broadly speaking, hydrogen sulfide and mercaptans that react with sodium plumbite to produce lead sulfide and other organic sulfur bodies, resulting in compounds which are not further acted upon by additional plumbite. The oil containing bodies which react with sodium plumbite is termed "sour" and an oil which does not react with plumbite is termed "sweet".

This plumbite solution which is obtained by the dissolution of lead oxide (i. e. litharge), in sodium hydroxide is known as "doctor solution".

The usual procedure is to mix, for instance, gasoline with the doctor solution and, in a common method, add enough sulfur to precipitate the lead which has formed oil-soluble organic compounds of lead. The precipitate is composed largely of lead sulfide, but contains also some organic compounds of lead. It has been proposed to recover lead from this lead sulfide precipitate in usable form:

One of these proposals consists in blowing air through the hot lead sulfide precipitate in the presence of sodium hydroxide solution. The probable reactions which occur are as follows:

While the above equation probably does not represent all of the conditions of reaction, it is at least illustrative of the changes which occur.

This invention relates to an improvement on the said process, its object is to carry out the initial doctor treatment so as to place the lead sulfide precipitate in the best possible form for recovery and subsequent use. This produces a recovered sodium plumbite of maximum efficiency. A further object is to increase the rate of the recovery reaction to the optimum conditions. I have found that the rate of oxidation increases with increase of temperature at any pressure and that the rate of reaction can be enormously increased with increase of pressure at any temperature. Thus, for example, in one case the maximum reaction

rate was increased three hundred times by raising the pressure from atmospheric to 100 pounds.

I have made the discovery, additionally, that whereas the rate of reaction at any pressure is increased with increasing temperatures, a limit is soon reached beyond which the increase in temperature results not in an increase of reaction rate, but actually in a rapid diminution of reaction rate such that for only a small further increase of temperature, the reaction rate will drop practically to zero. I have found as the boiling point of the solution at the pressure is approached, that the reaction rate drops off, and that when the boiling point is reached the reaction rate drops to zero. This phenomenon seems to hold irrespective of pressure. For example, the doctor solution which is normally used on a gasoline from liquid phase cracking consists of about 3 grams of lead oxide per 100 cubic centimeters of solution. The lead sulfide precipitate containing lead sulfide and sodium hydroxide is blown with air at 100° F. under atmospheric pressure, resulting in an increase of lead oxide in solution of 0.01 grams per 100 cubic centimeters per hour. An increase of temperature to 150° F. tripled this reaction rate producing a solution rate of 0.03 grams of lead oxide per 100 cubic centimeters per hour, but an increase of temperature from 150° to 180° produced no further increase in the reaction rate.

The reaction rate was again 0.03 grams of lead oxide dissolved per 100 cubic centimeters of solution per hour. It is to be noted that the boiling point of this doctor solution at atmospheric pressure is about 215° F. If this oxidation is carried out at 100 pounds absolute and at 150° the reaction rate is increased to about 2.5 grams per 100 cubic centimeters per hour, or about 80 times as rapid as the reaction at atmospheric pressure at the same temperature. By raising the temperature to 200° at 100 pounds pressure, the reaction rate is increased to about 6 grams per 100 cubic centimeters per hour. On raising the temperature to 275° the reaction rate is increased to about 9 grams per 100 cubic centimeters per hour, but on further raising the temperature to 300° F. the reaction rate falls to about 6.5 grams per 100 cubic centimeters per hour and if the temperature is raised to 325° the reaction falls to zero. It is to be noted that the boiling point of the doctor solution at 100 pounds is 330° F.

While I do not wish to limit myself to the following explanation of this peculiar action, I believe that this theory will explain what occurs. It is well known that chemical reactions are ac-

celerated by increase in temperature. Furthermore, this reaction is one between lead sulfide and oxygen and, therefore, will be increased by increase in concentration of oxygen in the solution. There are therefore, two ways in which this reaction will be accelerated; by increasing the temperature, and by increasing the pressure of the reacting gas. The increase in pressure, therefore, has a two-fold effect. It permits the maintenance of elevated temperature in the reaction mixture and also permits increase in partial pressure, that is, in concentration of the reacting gas. However, as the temperature of the material is increased under a given total pressure, the vapor pressure of water from the solution being reacted on will increase. This increase in vaporization will decrease the concentration of the reacting gas by decreasing its partial pressure. Therefore, the increase in temperature acts to diminish the reaction rate by increasing the partial pressure of the water vapor and decreasing the partial pressure of the reacting gas. It is well known that the vapor pressure curves are of logarithmic character, that is, that the rate of increase of vapor pressure with rise of temperature is slow at low temperature and becomes very steep, that is, rapidly increases, at more elevated temperatures. It is apparent, therefore, that at the lower temperatures increases in temperature do not result in any large increases in vaporization but as the temperature increases this vaporization increases at increasing rates. It is believed that this is the explanation of the peculiar change in reaction rate at any pressure as the temperature increases. The change may be visualized in the following manner. As the temperature increases, the reactivity, i. e., the reaction rate for a system of given composition increases, vaporization also increases, thus reducing the partial pressure of the reacting gas but the increase in temperature has caused a greater increase in reaction rate than the retardation in rate caused by the diminution of concentration of gas. A point is reached as the temperature is increased, when the increase in reactivity, due to increased temperature is more than compensated for by the decrease in rate caused by the diminution in partial pressure of the reacting gas, and therefore, further increase in temperature will cause diminution in reaction rate. This is actually what occurs in practice. It is apparent also, that as we approach the boiling point of the solution at the pressure employed, the concentration of reacting gas will drop to zero and that at the boiling point the reaction rate will be zero.

The conclusion which is to be drawn from the above explanation is that the reaction is best operated at as high a pressure as possible, and that the temperature shall be as high as possible, but less than the boiling point and in fact, shall be maintained preferably not greater than that temperature at which the reaction rate is at the maximum for the pressure employed. In the further discussion of this invention, that temperature will be called the optimum temperature and may be defined as that temperature at any given pressure at which the reaction rate is at the maximum. The reaction rate as herein discussed for purposes of convenience is the rate of formation of lead oxide in solution as plumbite, per unit of time, as for instance in the illustrative examples it is the rate of increase of lead oxide in grams per hundred cubic centimeters of solution per hour.

The above reaction converts the lead sulfide into sodium plumbite which may be used directly for further treatment of material such as sour gasoline. The separated lead sulfide sludge may be further regenerated and used over again. However, I have found that unless precautions are taken to remove emulsified gasoline from the doctor solution before it is regenerated, the regenerated doctor solution will discolor the treated gasoline. Gasoline, especially gasoline produced by a cracking process, on contact with doctor solution at elevated temperature is very rapidly discolored. Thus if the lead sulfide-alkali mixture contained emulsified gasoline the regenerated doctor solution when used over again would introduce these highly colored bodies into the gasoline which is being treated. Additionally the oxidation of emulsified bodies would produce organic acids which would increase the danger of emulsification when doctor solution is used over again. It is, therefore, highly desirable to separate the emulsified oil from the doctor solution before regeneration. An additional precaution is advisable to prevent the accumulation of substances in the regenerated doctor solution which would injure the oil subsequently treated. Some gasolines contain acidic compounds, either organic or in-organic which are preferably removed by a precaustic treatment before doctor treatment. This is especially true of gasoline treated with sulfuric acid and adsorbent clay and which would not otherwise receive an alkali treatment.

An additional modification which increases the rapidity of regeneration is the introduction of excess lead sulfide. Normal doctor solution, as has been indicated above, contains an amount of lead oxide equal to about 3 grams per 100 cubic centimeters and the spent doctor solution will therefore contain very little more than 3 grams of PbS per 100 cubic centimeters. The purpose of reaction is to convert this lead sulfide back to lead oxide. Instead of oxidizing the spent doctor solution as such, an amount of lead sulfide is added to the spent doctor to increase the lead sulfide content beyond that existing in the spent doctor. This increase in PbS will increase the solution rate. The recovery may be stopped when the solution contains 3 grams of PbO per 100 cubic centimeters and removed from the excess PbS, or the operation may be continued until the precipitate is nearly all dissolved, or until the solution contains as much as 6 to 9 grams of PbO per 100 cubic centimeters; this solution subsequently being diluted to proper strength by the addition of caustic solution. This invention will be better understood by reference to the drawings which accompany this case.

Figure 1 is a schematic illustration of an apparatus for carrying out this process.

Figure 2 is a flow sheet showing the course of the material.

Referring to Figure 1, gasoline which has received its acid and clay treatment to produce a gasoline of proper color is passed through 1, by means of pump 2 into an injector-type mixer 3, where it is co-mingled with separated alkali passing from separator 37 as will be further explained. This alkali is pumped by means of pump 41 into the mixer 3. This mixer operates to regulate the flow of alkali and gasoline at the proper proportions and to insure intimate mixture. The co-mingled alkali and gasoline is passed to separator 6 from which separated alkali is withdrawn through draw-off line 8. The alkali

150

treated gasoline is withdrawn through draw-off line 7 and is washed in 9 with water entering through 10. The co-mingled gasoline and water passes into a separator 12 from which water is withdrawn through 13 to the sump and gasoline is withdrawn by means of pump 14 and pumped through line 15 into mixer 16 wherein it is co-mingled with doctor solution passing from the second doctor treatment as will be hereinafter described. This doctor solution is pumped by pump 25 into mixer 16 and is co-mingled with gasoline from 15. The co-mingled material is passed to separator 18 from which the spent doctor solution is passed through line 20 and pump 35 to the regeneration step which will be hereinafter described. The gasoline passing from 18 through line 19 is pumped by pump 20 into mixer 21 here it is co-mingled with doctor solution pumped by pump 81 through line 22 into mixer 21. The co-mingled material is passed into separator 24 and, as hereinbefore described, the doctor solution is pumped by pump 25 into mixer 16 and the twice treated gasoline is passed through 26 by pump 27 to 28 where it receives a water wash by means of water introduced through 29. The co-mingled material is passed via 30 into separator 31 and the finished gasoline is drawn through 32 while water is withdrawn through 33 and pumped by pump 34 into 9 as hereinbefore described.

The spent doctor solution, as before stated, is pumped by pump 35 into heater 36 where it is heated by steam and passed into separator 37. In 37 the emulsified oil stratifies and rises in compartment 38 and is withdrawn through launders 39.

It is possible that oil vapors, generated by heating the material, may be liberated in the first compartment of the decanter and interfere with the settling. If so, the material can be carried to a gas trap above the decanter and returned by gravity from the trap to the decanter. The lead sulfide precipitates, together with such alkali solution as is to be used in the regenerating digestion, are withdrawn through 42 and the alkali, which is to be used for prewashing the gasoline and for diluting the strong regenerated doctor solution, is withdrawn through 40 and part of it, as hereinbefore described, is pumped to the pre-caustic treatment in 6, the remainder passing to 67 and 68. Part of the caustic may be diverted via 64 (a) by proper manipulation of 40 (a) to dilute the regenerated solution as described above. The lead sulfide with its accompanying alkali solution is introduced into 43. The purpose of this tank is to permit the continuous decanter to operate in conjunction with a continuous digester. It should have the capacity of at least twice the amount of material required to charge the digester. It is to be kept from one-fourth to three-fourths full in normal operation, providing sufficient reserves of material and storage space to care for any temporary lack of coordination between the preceding and succeeding operations. The material in the intermediate storage tank will have to be agitated sufficiently to prevent segregation, so as to supply material to the digester containing its proper quota of precipitate. The agitation may be either by low pressure air or the vent gases from the digester may be employed. Line 44 is provided for the introduction of air and 45 is for the introduction of vent gases. The material is withdrawn from storage tank 43 via line 47 through pump 48 and passed through preheater 49 and introduced into digester 51 via

line 50 and valves 62 and 61a; valves 63 and 61 being closed. By-pass 46 is provided whereby the material may be circulated and agitated and whereby the digester may be emptied into 43 if desired. Valve 61a and valve 61, when properly adjusted will permit this by-passing. The material is pumped into 51 when the valve 61a is closed, the other valves being properly adjusted. Steam is passed through heater 52 and air is introduced under high pressure through line 53, valve 54 and nozzles 55. Valve 56b is closed and valve 56a is regulated to maintain the desired pressure in 51. Some of the vent gas is passed through 56, 45 and 45a to maintain agitation in 43. The residual gas is passed through 57 and is re-compressed by recompressing blower 58 and reintroduced through 59 by nozzles 60. The reaction is carried on for the desired length of time.

When reaction has been completed, valve 54 is closed, recompression blower 58 is stopped and the charge is allowed to stand for a time sufficient to precipitate most of the suspended solids. The clear solution is blown out by closing 54 and opening valve 56b and closing valve 56a. The air pressure will blow the material through 64 into tanks 67 and 68. By providing another digester similar to 51 in parallel therewith, the process may be continued while 51 is being emptied. The material is introduced into tanks 67 and 68, as hereinbefore stated, depending upon which one is available, by opening the proper valve 65 and 66. These tanks are the storage tanks from which the material may be withdrawn by pump 81 via lines 79 or 80. Additional makeup tank 73 is provided in which additional plumbite may be generated by lead oxide introduced into the tank. Water is introduced via 71, controlled by valve 72, caustic solution through line 69, controlled by 70. Makeup may then be pumped by pump 74 into line 75, controlled by valve 77, and/or 115 through line 76, controlled by valve 78.

The operation of the plant is as follows:

Gasoline, for instance cracked gasoline which is given a sulfuric acid treatment followed by a treatment with decolorizing and neutralizing clay 120 is treated with doctor solution in the process described above.

Standard doctor solution, for example, may be composed of 3 grams of lead oxide and 10 grams of sodium hydroxide per 100 cubic centimeters. 125 When the solution is used in correct proportions, all the lead is precipitated chiefly as lead sulfide. All the caustic except for some that is neutralized by acid constituents of the gasoline, remains in the solution unchanged. Thus the caustic solution may be regarded like the water, as merely a vehicle for carrying the lead oxide which is the actual reagent. The amount of doctor solution required to treat a gasoline which has received a previous acid clay treatment is usually about 6% 130 by volume of the oil treated.

As has been previously pointed out, it is advisable to insure that the spent doctor solution is not contaminated by color bodies in order that the reclaimed doctor solution be as pure as possible and not contaminate the fresh gasoline to be treated thereby. In order to accomplish this the gasoline receives a precaustic wash followed by a water wash before it is treated by the doctor solution. In the process here described the caustic is obtained by settling of the spent doctor. When the spent doctor is treated to remove the emulsified oil this settling occurs at 37 and the clear alkali solution is removed as previously described by line 40 and pump 41. It is then intro- 150

duced as previously described by means of the mixer 3 together with gasoline into separator 6. The spent caustic is removed and this caustic treated gasoline is then water washed. The water used for this water wash is that which has been previously used to wash the gasoline passing from the doctor treatment. Thus the fresh water is introduced into 28 to wash the doctor treated gasoline and the water separated in separator 31 to pass into washer 9 where it meets the caustic treated gasoline and is finally discharged through 13. The gasoline is now ready for its doctor treatment. A two stage counter-current treatment is employed. The doctor solution is composed in substantial part of recovered doctor solution accumulated in tanks 67 and 68. Due to the fact that some lead is lost and due to the fact that some alkali is used up in the caustic treatment, make up is added from tank 73. Tank 73 is used as a mix tank and the doctor solution there mixed is added to 67 and 68 to bring it to standard strength. The doctor solution passes counter-current to the caustic and water washed gasoline in two stages. Gasoline passes first into stage 1, and then into stage 2, and doctor solution passes counter-current first, into stage 2, and then into stage 1. See flow sheet, Figure 2, Stage 2 represented in Fig. 1, by mixer 21 and separator 24. Stage 1, is represented by mixer 16 and separator 18. The water washed gasoline from separator 12 is passed by pump 14 into mixer 16 where it meets the once used doctor solution from separator 24. The doctor solution is removed by line 20 and pump 35 for regeneration. The once treated gasoline then passes into stage 2 by line 19, pump 20 and mixer 21 where it meets the doctor solution from tanks 67 and 68, passing via pump 81 and line 22, into mixer 21, than passing to separator 24. The gasoline from separator 24 is removed by line 26 and pump 27 and introduced into 28 where it receives its water wash. The mixture of water and gasoline passes to line 30 into separator 31, finished gasoline being removed through 32 and the water being removed by line 33 and pump 34 as previously described, to be used to wash the gasoline which has received its precaustic wash.

The regeneration of the spent doctor will now be described.

The first step in this reclamation process is the removal of emulsified gasoline in the spent doctor. The spent doctor is pumped by pump 35 through heater 36 which may be heated by exhaust steam and is preferably heated to 160° F. If the treatment is continuous the hot doctor solution from the digester 51 could be used as a source of heat in heat exchanger 36. The thus heated spent doctor solution then passes into decanter 37. The emulsified oil which is stratified is overflowed through launder 39 as previously described. Some segregation of lead precipitate and caustic occurs. The caustic is removed through line 40 as previously described, in necessary amounts for the precaustic treatment. About 10% of the caustic is thus removed and also such caustic solution as is not required in the digester may be by-passed to 67 and 68.

The remainder of the caustic and the spent lead are underflowed by line 42 into intermediate tank 43. This tank is used when discontinuous digestion is employed. If the digestion is of a continuous nature this tank would be by-passed and the digester fed directly from the decanter. The purpose of this intermediate stage tank 43 is to permit the discontinuous decanter to oper-

ate in conjunction with the discontinuous digester. It should have a capacity of at least twice the amount of material required to charge the digester. It is to be kept from one-quarter to three-fourths full in normal operation, providing sufficient reserves of material and storage space to take care of any temporary lack of co-ordination between the preceding and succeeding operations. The material in the intermediate stage tank will have to be agitated sufficiently to prevent segregation so as to supply material to the digester containing its proper quota of precipitates. To accomplish this, air is blown through the tank. Vent gases from the digester may also be employed as in Fig. 1, vent gases being introduced through 45. This agitation will cause some evaporation and the temperature of the material in the intermediate tank 43 will adjust itself to about 140° F.

The material is withdrawn through line 47 and pump 48 and is heated in heater 49 to about 200° F. The digestion in digester 51 will be carried on as previously described in the presence of an excess of spent lead. That is, at the start of the digestion there will be present an amount of precipitate equivalent to from 6 to 12 grams of PbO per 100 cubic centimeters of solution, and at the end of the digestion about 3 grams per 100 cubic centimeters; from 3 to 9 grams per 100 cubic centimeters having passed into solution. The remaining precipitate will be left to supply the excess for the following charges. This arrangement maintains the reaction rate at a high point throughout the whole of the digestion period. Without this additional amount of lead, the reaction rate would drop off as the lead is dissolved.

During the digestion fresh air will be supplied through line 53 into spider 55 under an elevated pressure of about 95 or 100 pounds absolute. The gases are vented through valve 56a to maintain this pressure and steam is passed through heater 52 to maintain the elevated temperature of about 200° F. The air which is blown into the digester 51 acts both to oxidize the lead sulfide and also to agitate the mixture to keep the precipitate in suspension and thoroughly mixed. When more air is required for agitation than is required to supply oxygen for oxidation, it has been found economical to recycle vent gases via line 57 and re-compression blower 58 and introduce the same through line 59 into the digester 51. Under these circumstances it is only necessary to supply through 53, the air necessary for oxidation, the agitation being supplied by the re-introduced gases through 59. This digestion continues until the desired solution is obtained.

At the end of the treatment the air is shut off as previously described and the excess lead sulfide allowed to settle. This settling occurs within an hour. The clear liquor is discharged through the side opening and, valve 64a being opened, air pressure, introduced by means of 53a with the proper adjustment of valves of 56a and 56b as previously described, is employed to discharge the material. The excess lead sulfide remains in the digester and is ready for a second treatment. The recovered doctor solution is discharged through line 64 and receives its make up in tanks 67 and 68.

It is to be observed that whereas the maximum obtainable reaction rate at 100 pounds absolute is at 275° F., the reaction here carried out was at 200° F. The reason for this is that it is more

55 economical where exhaust steam is available to operate at a lower temperature.

In general, the conditions chosen for a reaction in commercial operation are those which will 5 give a product of lowest cost consistent with satisfactory quality. Reaction rate enters into a consideration of cost principally in that it affects the size of equipment required for a definite daily production. The size of equipment in turn affects 10 the operating cost because of the necessity of making an allowance for maintenance, interest, and depreciation as a percentage of the initial cost of the equipment. It should be pointed out, however, that these items are not necessarily 15 the most important factors in the total cost of operation. In the present case, the point of maximum economy will probably be found to be somewhat before the point of maximum rate. The reason for this is that at the point of maximum 20 rate and beyond it, there will be a large amount of evaporation of water from the solution which, in turn, will necessitate supplying large amount of heat to furnish the heat of vaporization. In fact, as the point of maximum 25 rate is passed, the quantity of water vaporized approaches infinity as the rate approaches zero. It is therefore advisable as is here described to operate below the temperature of maximum reaction rate. However other conditions may make 30 advisable the operation at as near that temperature as possible. The man skilled in the art will be able to use proper adjustments.

35 While I have spoken of using air as the most useful oxidizing agent, other oxidizing gases such as pure oxygen or ozone may be employed.

In like manner whereas the carrying agent has been described as sodium hydroxide other equivalent caustics may be used as well as other equivalent reagents.

40 The above disclosure is therefore not to be taken as limiting the scope of my invention but is merely illustrative thereof and of the best manner of carrying this out and can be modified within the scope of my invention which I claim 45 to be:—

1. A method for regenerating spent doctor solution containing lead sulfide which comprises heating the lead sulfide and contacting the said lead sulfide with an oxidizing gas under superatmospheric pressure and at a temperature below the 50 boiling point of the solution at such superatmospheric pressure.

2. A method for regenerating spent doctor solu-

tion containing lead sulfide which comprises heating the lead sulfide and sodium hydroxide solution under superatmospheric pressure and contacting the said lead sulfide with an oxidizing gas at a temperature below the boiling point of the solution at such superatmospheric pressure.

3. A method for regenerating spent doctor solution containing lead sulfide which comprises heating the lead sulfide and sodium hydroxide solution under superatmospheric pressure and contacting the said lead sulfide with an oxidizing gas and maintaining the temperature of the reaction not above the optimum temperature for aforesaid pressure.

4. A method for regenerating spent doctor solution which comprises treating gasoline with doctor solution, withdrawing the gasoline from the spent doctor solution, adding additional lead sulfide to the spent doctor solution, contacting mixture with an oxidizing gas at a superatmospheric pressure at an elevated temperature, but not above the optimum temperature for such pressure, and withdrawing the thus regenerated doctor solution.

5. A method for regenerating spent doctor solution which comprises treating gasoline with doctor solution, withdrawing the gasoline from the spent doctor solution, adding additional lead sulfide to the spent doctor solution and contacting the mixture with an oxidizing gas at an elevated temperature and at a superatmospheric pressure and maintaining the temperature at not above the optimum temperature at said pressure and withdrawing regenerated doctor solution.

6. A method for regenerating spent doctor solution containing lead sulphide which comprises heating lead sulphide and sodium hydroxide solution under a pressure from 40 to 100 lbs. per square inch, and contacting the said lead sulphide with an oxidizing gas and maintaining the temperature of the reaction not above the optimum temperature for said pressure.

7. A method for regenerating spent doctor solution containing lead sulphide which comprises heating lead sulphide and sodium hydroxide solution under a pressure of 100 lbs. absolute, contacting the said lead sulphide with an oxidizing gas and maintaining the temperature of the reaction between 200 and 300° F.

8. In a method according to claim 7 wherein the reaction is carried out at the temperature of about 275° F.
